DUPLEX GRINDING MACHINE

John Bath and Stanley W. Bath, Shrewsbury, Mass., assignors to John Bath & Company, Worcester, Mass., a corporation of Massachusetts

Application March 6, 1933, Serial No. 659,704

10 Claims. (Cl. 51—3)

This invention relates to a grinding machine of the duplex type in which separate grinding operations may be simultaneously performed on two different pieces of work.

5 It is the general object of our invention to improve the construction of such duplex grinding machines in many important respects, to the intent that the machine may be more perfectly adapted to its intended purposes.

10 To the attainment of this general object, one feature of our invention relates to the provision of an improved power cross feed mechanism for the work table, together with means for separately feeding either wheel head manually toward 15 or away from the work.

We also provide power means for giving each wheel head a limited movement toward and away from the work, as for a so-called "plunger cut".

Other features of the invention relate to means 20 for disconnecting and manually feeding the work table longitudinally, to an improved double swivel table construction, and to the provision of improved hydraulic feeding and control mechanism.

Our invention further relates to arrangements 25 and combinations of parts which will be herein-after described and more particularly pointed out in the appended claims.

A preferred form of the invention is shown in the drawings, in which

30 Fig. 1 is a front elevation of our improved machine;

Fig. 2 is a plan view, looking in the direction of the arrow 2 in Fig. 1;

Fig. 3 is an end elevation, looking in the direction of the arrow 3 in Fig. 1;

Fig. 4 is a sectional front elevation, taken along the line 4—4 in Fig. 2;

Fig. 5 is a diagrammatic view of the hydraulic feeding and control mechanism;

40 Fig. 6 is an enlarged sectional front elevation of a table release device;

Fig. 7 is an enlarged front elevation of certain table feeding mechanism;

Fig. 8 is a further enlarged front elevation of 45 certain parts shown in Fig. 7 but in a different position;

50 Fig. 10 is a partial plan view of the work slide, with the swivel tables mounted thereon;

Fig. 11 is a partial front elevation, looking in the direction of the arrow 11 in Fig. 10;

Fig. 12 is a sectional end elevation, taken along 55 the line 12—12 in Fig. 10;

Fig. 13 is a side elevation of one of the wheel heads and certain associated parts;

Fig. 14 is an enlarged sectional front elevation, taken along the line 14—14 in Fig. 13;

Fig. 15 is an enlarged detail side elevation, 5 taken partly in section along the line 15—15 in Fig. 14;

Fig. 16 is an enlarged sectional detail view of certain cam adjusting mechanism, taken along the line 16—16 in Fig. 15; 10

Fig. 17 is an enlarged side elevation of a cam, partly in section and taken along the line 17—17 in Fig. 16;

Fig. 18 is a front elevation of the cam, looking in the direction of the arrow 18 in Fig. 17; 15

Fig. 19 is a front elevation, partly in section, showing portions of the two wheel heads and a single grinding wheel jointly supported thereby;

Fig. 20 is a side elevation of certain valve 20 mechanism for effecting the plunge cut;

Fig. 21 is a sectional diagrammatic view showing a hydraulic actuating and control mechanism for the plunger cut;

Fig. 22 shows certain of the parts appearing in 25 Fig. 21 but in a different position, and

Figs. 23 to 28 inclusive illustrate different uses for our improved machine.

Referring to Figs. 1, 2, and 3, our improved duplex grinding machine comprises a base or frame F supporting a pair of wheel heads W and W' and a reciprocating table T having work heads H and H'. Motors M and M' are provided for the wheel heads W and W', additional motors A and A' for the work heads H and H' and a motor B for the pump P (Fig. 4). 35

Work table

We will first describe our improved work table and the associated devices by which two pieces of work may be simultaneously mounted and 40 rotated thereon, and by which desired movements of the table, both longitudinally and transversely, may be obtained.

The work table T (Figs. 10 to 12) is slidably longitudinally in a V-shaped guideway 38 in a 45 support S and also on a flat bearing surface 31 thereof. The support S (Fig. 4) is slidable transversely on bearing surfaces 381 and 382 of the frame F and is guided by a cross member 383.

A pair of swivel tables 32 and 33 are pivoted 50 at 34 and 35 on the table T and are provided with tail stocks 36 and 37 slidable on the swivel tables 32 and 33 and secured in adjusted position thereon by clamping bolts 38. Tail centers 48 are slidable in the tail stocks 36 and 37 and 55

may be secured in adjusted position by binding screws 41.

The adjacent ends of the tables 32 and 33 are formed as segmental arcs centered at the pivots 34 and 35, and are provided with arcuate grooves 42 positioned to receive similarly shaped flanges 43 on a wedge-shaped clamping block 44 secured in position by binding screws 45. The curved end portions of the tables 32 and 33 may be beveled and provided with index marks 46 (Fig. 10), and the clamping block 44 may be graduated as indicated at 47, so that setting of the swivel tables at desired angles may be facilitated.

For the purpose of convenient setting, we also provide each table 32 or 33 with an adjusting screw 48 (Fig. 10) rotatable in a bearing projection 49 on the table T but held from axial movement therein by a collar or shoulder 50. Each adjusting screw 48 is threaded into a swivel nut 51 pivoted at 52 to a lug or bracket 53 projecting from the adjacent end of the swivel table 32 or 33.

When the clamping screws 45 are loosened, the adjusting screws 48 provide convenient means for swinging the tables to any desired angular positions and the screws 48 also provide for retaining either table in adjusted position when the clamping block 44 is loosened to permit adjustment of the other table.

The work heads H and H' (Fig. 2) are mounted on the swivel tables 32 and 33 and are provided with work-supporting centers 55 and with suitable reduction and change gear driving connections by which the work may be rotated at desired speeds by the motors A and A'. The specific driving mechanism of the work heads H and H' forms no part of our present invention and further description thereof appears unnecessary.

Table feed

The table T is preferably provided with a piston rod 60 (Fig. 5) connected to a piston 61 slidable in a cylinder 62 fixed in the frame F and connected with hydraulic actuating mechanism to be described.

We have made special provision for disconnecting the table T from the piston rod 60 when it is desired to slide the table T longitudinally by hand. For this purpose the rod 60 is provided with an enlarged head 63 (Fig. 6), also with an annular groove 64 and a cone-shaped end portion 65.

A latch 66 is mounted on a plunger 67 and is slidable in a laterally projecting bearing portion 68 of the table T. A coil spring 69 yieldingly forces the latch 66 to the normal or locked position shown in Fig. 5.

A bell crank 70 is pivoted at 71 on a bracket 72 depending from the table T, and the forked end 73 of the bell crank engages the outer end of the stud 67 between shoulders 74 and 75 thereof. A hand lever 76 is pivoted at 77 on the bracket 72 and has a cam portion 78 adapted to engage the second arm of the bell crank 70.

When the hand lever 76 is in the position shown in Fig. 5, the latch 66 is in operative or locking position, but when the lever 76 is swung to the position shown in full lines in Fig. 6, the bell crank 70 withdraws the latch 66 and releases the piston rod 60.

A rack 80 (Figs. 7 and 9) is provided on the under side of the table T. A shaft 81 (Fig. 9) is mounted in a bearing 82 on an apron 83 secured to a front portion of the support S. A hand wheel 84 is fixed to the front end of the shaft 81, and a pinion 85 is fixed to the rear end of the shaft 81.

A gear 86 is mounted on an arm 87 secured to one end of a sleeve 88 concentric with the shaft 81 and extending through the bearing 82.

An arm 89 is formed on or secured to the outer end of the sleeve 88 and is provided with a spring 5 plunger 90 adapted to be seated in either one of two holes 91 formed in a lower thickened portion of the apron 83. A knob or handle 92 is provided for withdrawing the spring plunger 90. When positioned as shown in Fig. 7, the gear 86 engages 10 the rack 80 and the table T can be moved longitudinally by means of the hand wheel 84 after the table is released from the piston rod 60.

After the table is again connected to the rod 60, the plunger 90 will be placed in the left-hand 15 hole 91 in the apron 83, thus swinging the gear 86 downward out of mesh with the rack 80.

Table cross feed

Our improved automatic cross feed for the table 20 T is shown in Figs. 3, 7 and 8 and comprises a cross feed screw 95 (Fig. 3) rotatable in but held from axial movement relative to bearings 96 and 97 in the frame F and threaded into a nut 98 secured in a depending projection 99 on the table 25 support S.

The cross feed screw 95 is connected through a train of gearing 100 to a feed shaft 101 (Fig. 7) having a gear or ratchet wheel 102 fast thereon.

A hand wheel 103 is loosely rotatable about the 30 axis of the shaft 101 and is detachably connected to the gear 102 by a pinion mounted at the rear end of a spring-pressed plunger 104. The plunger 104 is slidable axially when it is desired to disconnect the hand wheel from the gear 102 and the plunger 35 is also connected through intermediate gears (not shown) to an arm 105, also loosely rotatable about the axis of the gear 102 but normally connected to the hand wheel 103 by a stud 106, adapted to be inserted in any one of a series of holes 40 107 formed in the hand wheel 103. A shoulder 108 on the hand wheel engages a stop plate 109 on the apron 83, which stop plate may be placed in operative or inoperative position as desired.

When the stud 106 is inserted in one of the holes 45 107 and the pinion on the plunger 104 engages the gear 102, the hand wheel 103 is locked to the gear 102. Consequently, when the shoulder 108 on the hand wheel engages the fixed stop 109, the gear 102 and cross feed screw 95 are stopped 50 in a fixed and predetermined position.

If it is then desired to make a fine and accurate adjustment of the transverse position of the support S, the stud 106 is withdrawn and the arm 105 55 is swung in one direction or the other, thus turning the pinion on the plunger 104 relative to the gear 102.

When the necessary adjustment has been made, the stud 106 is inserted in another hole 107 and the amount of adjustment may be estimated by 60 the number of spaces by which the stud is advanced. When it is not desired to stop the cross feed at a predetermined point, the stop plate 109 is withdrawn to inoperative position.

A pawl lever 110 is pivoted at 111 to a feed 65 lever 112 mounted on a stud 113 on the apron 83 and having a V-shaped cam plate 114 adjustable thereon. A spring 115 holds the pawl 110 yieldingly in engagement with the ratchet wheel 102 but permits the same to be withdrawn therefrom when manual adjustment is desired. A spring 116 normally pulls the lever 112 upward to engage a stop pin 117.

A stud 120 (Fig. 8) is supported on an arm 121 70 clamped on a piston rod 122, which rod is slidable 75

in a bearing plate 123 secured to the apron 83 and is connected to a piston 124 mounted in a cylinder 125 which is also supported on the apron 83.

5 Suitable hydraulic connections to be described are provided for admitting fluid under pressure to one end or the other of the cylinder 125, thus giving the piston rod 122 and stud 120 alternate movements in opposite directions.

10 The normal position of the parts is as shown in Fig. 7, with the stud 120 at one side or the other of the cam plate 114. As the piston is reciprocated, the stud passes under the high point of the plate 114 as indicated in Fig. 8, giving the 15 feed lever 112 a feeding movement. The extent of this movement may be varied by adjusting the cam plate 114 in the end of the lever 112.

For this purpose, a screw 125 is mounted for rotation but not for axial movement in a recess 20 in the cam plate 114, and is threaded in a bearing portion 126 of the feed lever 112. By turning the screw 125, the cam plate 114 may be forced outward or drawn inward on guide pins 127, and when thus adjusted, may be secured by a wing 25 nut 128.

By adjusting the cam plate 114 downward, the stud 120 will be engaged earlier and the feed lever 112 and pawl 110 will obviously be given a greater feeding movement.

30 *Automatic work table travel*

For automatically controlling and reversing the longitudinal travel of the work table T, we provide control mechanism C (Fig. 7) which is connected to the pump P by an inlet pipe 140 (Fig. 5) and which is connected by an exhaust pipe 141 to a tank 142 from which the pump P draws liquid supply through a feed pipe 143.

The control mechanism C is also connected 40 by a pipe 144 to one end of the table operating cylinder 62 and by a pipe 145 to the opposite end of the cylinder 62. An automatic reversing and manual control lever or handle L (Fig. 7) projects upward from the control mechanism C and is alternately engaged by reversing dogs 146 and 45 147, mounted for longitudinal adjustment in a T-shaped slot 148 (Fig. 12) in the edge of the table T.

Reversing or trip valves 150 and 151 (Fig. 7) 50 are connected for actuation by the handle L and control the reversal of the hydraulic connections to the cylinder pipes 144 and 145. A speed control valve (not shown) is also provided, which may be adjusted manually by moving an arm 153 to a position corresponding to a selected graduation on the scale 154.

The details of this speed control and reversing mechanism are not shown or claimed herein, as this mechanism forms part of the subject-matter 60 of the prior application of Stanley W. Bath, Serial No. 611,861, filed May 17, 1932 now U. S. Letters Patent No. 1,946,348, granted February 6, 1934, to which patent reference is made for a more complete description.

65 *Wheel slides and feeding mechanism therefor*

Referring particularly to Figs. 13 to 19, we have 70 provided right and left wheel heads W' and W which are substantially duplicates of each other, so that a description of the wheel head W will apply also to the wheel head W'.

The wheel head W comprises a wheel slide 160 (Figs. 13 and 14) slidable forward and rearward in a guideway 161 and on a guiding surface 162, both formed on the frame F. A wheel X is

mounted on a spindle 163 (Fig. 19) rotatable in a suitable bearing portion 164 of the wheel slide 160, and preferably driven by a belt 165 from the associated motor M or M'.

The wheel spindles 163 may have a slight oscillating axial movement during operation, as is customary in grinding machines of this type, and each wheel head may be provided with an arm and handle 166 by which the wheel spindle may be moved outward a short distance for a purpose 10 to be described.

Ordinarily a separate grinding wheel X will be provided for each wheel head and will separately engage the work. It may at times be desirable, however, to use a single wide-face wheel X' (Fig. 15 19), and to support this single wheel between the two wheel spindles 163, so that the power of both motors M and M' may be utilized to drive the single wide wheel.

When it is desired to operate in this manner, we 20 provide a spindle extension 170 for each spindle 163, said extension being accurately centered on a conical end portion of the spindle and being firmly secured thereon by a washer or collar 171 and binding nut 172.

The wheel X' is preferably provided with hub 25 members 175, inserted from each side of the wheel and accurately centered therewith. These hub members are firmly secured together by binding screws 176 and are preferably recessed to receive 30 projecting end portions 177 of the spindle extensions 170. The extensions 170 are firmly secured to the hub members 175 by binding screws 178 after the wheel spindles have been adjusted forward or rearward into accurate alignment. 35

Clamping screws 180 (Fig. 19) are provided for 40 securing the wheel heads 160 in such aligned positions. Either spindle 163 may be withdrawn axially by the associated handle 166 to permit insertion or removal of the wheel X'.

When thus supported, it will be evident that the wheel X' is in effect mounted on a long wheel shaft having spaced bearings of substantial extent, said shaft being driven from each end by separate belts 165 and motors M and M'. We 45 are thus able to more firmly support and drive the wheel in engagement with the work K.

40 *Wheel feed mechanism*

Referring particularly to Figs. 13 to 18, we will 50 now describe the mechanism for feeding the wheels X toward and from the work K. For this purpose each wheel slide 160 is provided with a lead screw 184 (Fig. 15) rotatable in but held from axial movement relative to a bearing 185 55 at the rear of the wheel slide 160.

The lead screw 184 is connected by a bevel gear 186 and bevel pinion 187 to a feed shaft 188 extending upwardly and forwardly and supported 60 in bearings 189 on the wheel slide 160, said shaft 188 being provided with a handle 190 at its upper forward end. The forward end of the bearing 189 may be enlarged, as indicated at 191, to provide a graduated scale with reference to which the extent of manual movement of the handle 65 190 may be noted.

The lead screw 184 is threaded into a nut 193 (Fig. 15) which is clamped in position in a block 194 slidable in a dove-tailed guideway 195 (Fig. 14 in the frame F. The block 194 has depending arms 196 provided with rolls 197 engaging opposite sides of a cam 200 (Fig. 17). The cam 200 is given intermittent oscillating movements by mechanism to be described and in every position determines the location of the block 194 75

and lead screw nut 193. Assuming that the block and nut are held stationary, movement of the handle 190 manually advances or withdraws the wheel with respect to the work K.

5 The cam 200 is of a special construction more particularly disclosed in Figs. 14 to 18. The cam is mounted on a sleeve 201 rotatable in bearings 202 (Figs. 14 and 16) in the frame F, and is provided with an arm 203 fixed to the sleeve 201 and connected at its outer end by a link 204 (Fig. 13) to the outer end of a piston rod 205 connected to a piston 206 slidable in a fixed cylinder 207.

15 As fluid under pressure is admitted to one end or the other of the cylinder 207 through control mechanism to be described, the piston will be moved in the cylinder and will cause a corresponding rocking movement of the cam 200.

20 The cam 200 comprises inner concentric portions 210, a raised portion 211, an outer concentric portion 212 and a movable cam plate 213 pivoted at 214 to the concentric portion 212 of the cam 200. The cam plate 213 has a portion 215 which is concentric with the pivot bearing 214 thereof and also has a portion 216 which merges at one end with the outer concentric portion 212 of the cam 200 but which at the other end is eccentric thereto and positioned at a less distance from the axis of the cam 200.

25 The movable cam member 213 also has an abruptly rising portion 217 and an arm 218 provided with a stud 219 extending through a slot 220 (Fig. 16) to the interior of the sleeve 201.

30 A spring plate 221 extends laterally from the stud 219 and is secured to the outer surface of the sleeve 201 as clearly shown in Figs. 16 and 17, this spring acting to force the stud 219 and arm 218 inward towards the axis of the sleeve. A plunger 224 is mounted within the sleeve 201 and is provided with a cone-shaped end 225 engaging the inner end of the stud 219.

35 At its opposite end, the plunger 224 is provided with a threaded portion meshing with an internal screw thread of the sleeve 201 and is further provided with a squared end portion 226 extending outward through a square opening in an arm 227. The arm 227 is rotatably mounted on the outer end of the sleeve 201 and is connected to the arm 203 by a spring plunger 228.

40 By withdrawing the spring plunger 228 (Fig. 14) the arm 227 may be rotated while the sleeve 201 remains in fixed position, thus adjusting the plunger 224 axially of the sleeve.

45 If the plunger is moved inward, the stud 219 and cam arm 218 will be moved outward, so that the portion 216 of the cam member 213 more nearly approaches the concentric surface 212, thereby reducing the rate of wheel feed after the forward roll 197 engages the surface of the portion 216.

50 This method of feed is used when a grinding wheel is to be moved directly forward against the work for a so-called "plunge-cut" without axial feed of the wheel or work.

55 In the normal or rearward position of the block 194, the rear roll 197 is engaged by the inclined face of the portion 211 of the cam 200 and the block 194 is thus held firmly in withdrawn and fixed position.

60 If a "plunge cut" is desired, fluid under pressure is admitted to the rear end of the cylinder 207, thus giving the cam 200 a clockwise rocking movement which first causes the forward roll 197 to be engaged by the part 211 of the cam member 213, advancing the wheel somewhat rap-

idly toward the work. This preliminary movement may be of substantial extent, usually about one-quarter of an inch.

65 The parts are so adjusted that the forward roll 197 will be engaged by the surface 216 of the cam member 213 as the wheel engages the work. The roll 197 then travels on the slight incline of the surface 216 until the concentric surface 212 is reached, by which concentric surface the wheel is held in fixed position for a 10 final or finish grinding operation. The pressure connections to the cylinder 207 are then reversed, withdrawing the wheel and bringing the parts to rest in initial position, where they will remain until again manually started in opera- 15. 15.

Wheel feed control mechanism

20 The mechanism by which the liquid supplied to the cylinder 207 is controlled is shown in Figs. 20 to 22. This mechanism is connected by an inlet pipe 230 to the liquid supply pipe 148 previously described and is likewise connected by an exhaust pipe 231 to the storage tank 142 (Fig. 5). It will be understood that there is a cylinder 207 for 25 each wheel head and that the supply pipe 230 and exhaust pipe 231 are branch connected (Fig. 5) to both wheel feeding cylinders.

25 The control mechanism for each cylinder 207 includes a speed valve 233 (Fig. 21), a reversing 30 valve 234 and a pair of trip valves 235 and 236. The reversing valve cylinder 237 is connected by a pipe 238 to one end of the cylinder 207 and by a pipe 239 to the opposite end of the cylinder 207. The reversing valve cylinder 237 is also connected 35 by branch pipes 240 and 241 to a pipe 242 which in turn connects with the exhaust pipe 231.

30 The pipe 242 also connects to a port in the casing of the trip valve cylinder 243 and an additional pipe 244 connects another port in the cylinder 243 to one end of the reversing valve cylinder 40 237. The cylinder 245 for the trip valve 236 is similarly connected by a pipe 246 to the exhaust and by a pipe 247 to the opposite end of the reversing valve cylinder 237.

35 The inlet pipe 230 is connected by branch pipes 250 and 251 to ports in the trip valve cylinders 243 and 245 respectively, and the inlet pipe 230 is also connected through the speed control valve 233 and through a branch pipe 253 to an additional port in the center of the length of the reversing valve cylinder 237.

40 The trip valve 235 is provided with recesses 255 and 256 and with a bell crank lever 257 (Fig. 20) secured to one end thereof and by which the valve may be operated. The trip valve 236 is similarly provided with recesses 260 and 261 and with an arm 262 adapted to be engaged by an extension of the piston rod 205.

45 A tension spring 264 (Fig. 20) connects the bell crank 257 to the arm 262 and holds these parts normally against stop pins 265 and 266. When the trip valves are in normal position, pressure is applied through the pipes 244 and 247 to both ends of the reversing valve cylinder 237, so that the reversing valve 234 is under equal pressures in both directions and there is no unbalanced force tending to move the valve.

Operation of wheel feed control

50 A piston 270 (Fig. 20) in a small cylinder 271 is connected by a piston rod 272 to the bell crank 257 of the trip valve 235. Fluid under pressure is supplied through a pipe 273 and is controlled by a manually operated valve 274 which may be conveniently located at the front of the machine. 70. 75.

When it is desired to set the automatic wheel feed in operation, the valve 274 is temporarily opened to admit pressure to the cylinder 271, thus rocking the trip valve 235 in an anti-clockwise direction. The pipe 244 is thus connected to the exhaust pipe 242, while pressure is maintained in the pipe 247 at the opposite end of the reversing valve cylinder 237. The reversing valve 234 is thus moved from the position shown in Fig. 21 to that shown in Fig. 22.

Liquid under pressure then flows from the pipe 253 through the cylinder 237 to the pipe 239 connected to the left-hand end of the feed cam operating cylinder 207. This causes the piston 206 to move to the right in Fig. 21, giving the cam 200 a clockwise feeding movement as indicated by the arrow *a* in Fig. 17.

As this movement of the piston 206 to the right approaches completion, the projecting end of the piston rod 205 engages the trip valve arm 262 and rocks the trip valve 236 clockwise to the position shown in Fig. 21, with the feed pipe 251 disconnected from the reversing valve cylinder and with the pipe 247 connected to the exhaust pipe 246.

The starting valve 274 is opened only momentarily and the valve 235 has been previously restored to the position shown in Fig. 21 by the spring 264, thus connecting the pipe 244 to the pressure pipe 250. Consequently the reversing valve 234 is immediately returned to the position shown in Fig. 21, connecting the pressure pipe 253 through the pipe 238 to the right-hand end of the cylinder 207 and moving the piston 206 to the left and back to initial position.

It will thus appear that for a single momentary opening of the valve 274, the cam 200 will be given an operative clockwise feeding movement followed automatically by a return movement to initial position.

Valves 275 and 276 in the pipes 242 and 246 may be adjusted to control the rate of exhaust from the reversing valve cylinder 237 and thus control the rate of valve travel.

The speed valve 233 (Fig. 21) is provided with a central passage 277 and with a series of radial passages 278 of different cross sectional areas. The speed valve 233 may be turned by a handle 279 to bring any selected radial passage 278 in alignment with the pipe 253, thus varying the rate of flow to the cylinder 205. A graduated dial 280 is preferably associated with the handle 279.

General hydraulic operation

The general operation of the hydraulic mechanism is shown diagrammatically in Fig. 5. The pump *P*, as previously stated, is connected by a feed pipe 140 to the control valve mechanism *C* by which the flow of liquid through the pipes 144 and 145 to the main cylinder 62 is controlled. A relief valve 282 (Fig. 5) prevents the building up of excessive pressure in the feed pipe 140.

The cross feeding cylinder 125 for the work table support *S* is connected in parallel with the main cylinder 62 so that the piston 124 (Fig. 8) receives movements at the same time and in the same direction as the main piston 61.

By reference to Figs. 7 and 8 it will be seen that movement of the piston 124 in either direction effects an advance or feeding movement of the gear or ratchet wheel 102, so that the cross feed operates at each reversal of the work table travel.

The feed pipe 230 and exhaust pipe 231 for the wheel feed cylinders 207 are continuously connected to the feed pipe 140 and to the exhaust,

so that the wheel feed cylinders 207 may be started in operation at any time.

We also preferably provide wheel truing devices *D* and *D'* (Fig. 5) connected to the feed pipe 230 and exhaust pipe 231 and operable by hydraulic mechanism under the control of the operator.

General operation

Our improved grinding machine has a very wide range of utility and is extremely flexible in its operation, due particularly to the provision of separately swiveled tables and to the provision of separately controlled wheel feed mechanism for each wheel head.

As previously explained, both wheel spindles may be utilized to drive a single wide face grinding wheel as shown in Fig. 19, and in Figs. 23 to 28 we have shown a series of combinations by which the wide adaptability of the machine is illustrated.

In Fig. 23 both grinding wheels *X*² and *X*³ are employed in making plunge cuts without relative axial movement of the wheel and work, and the two pieces of work are rotated on the same axis.

In Fig. 24 the wheel *X*² is grinding a cylindrical surface while the wheel *X*³ is grinding a conical surface at the same time, one swivel table having been adjusted to produce the conical surface.

In Fig. 25 the wheel *X*² is grinding a conical surface of one taper and one diameter, while the wheel *X*³ is grinding a conical surface of a different taper and diameter.

In Fig. 26 both wheels are grinding cylindrical work but of different diameters, and in Fig. 27 the wheels are of different widths and are grinding conical surfaces of different diameters and different tapers.

In Fig. 28 the wheel *X*² is grinding a straight cylindrical surface and the wheel *X*³ a conical surface and both surfaces are being ground simultaneously as the work table reciprocates.

It will be obvious that the number of possible combinations for which our machine is adapted is practically unlimited. The machine may be operated with or without longitudinal table feed, either manual or automatic, with an automatic cross feed of the table, with manual wheel feed of either grinding wheel, and also with an automatic advance and return movement of either grinding wheel.

Suitable provision has been made also for varying the rate of feed of the various feeding devices.

While we have shown our invention embodied in a machine for grinding work on centers, it will be obvious that many features of the invention are not limited in their utility to such a machine but may be utilized in other types of grinding machines such as centerless grinders or machines in which the work is chucked.

Having thus described our invention and the advantages thereof, we do not wish to be limited to the details herein disclosed, otherwise than as set forth in the claims, but what we claim is:

1. A grinding machine having a grinding wheel, a wheel head, means to move said wheel head toward and from the work, a work table, a support for said table, automatic means to move said table longitudinally, and automatic means to feed said support toward said grinding wheel at each reversal of table travel, said automatic means including a hydraulic cylinder and piston to move said work table longitudinally, and an additional hydraulic cylinder and piston to actu-

- ate said support-feeding means, said two cylinders being connected in parallel and operating simultaneously at the beginning of each table movement after each reversal of table travel.
- 5 2. A grinding machine having a grinding wheel, a wheel head, manual means to move said wheel head toward and from the work, and hydraulically actuated automatic means to advance said wheel to a predetermined position and to thereafter withdraw said wheel and hold said wheel in withdrawn position, said automatic means including a rotating cam, connections through which said cam is effective to move said wheel head, and connections through which 10 said automatic means gives said cam successive angular movements in opposite directions and brings said cam to rest in initial position.
- 15 3. A grinding machine having a grinding wheel, a wheel head, manual means to move said wheel head toward and from the work, and hydraulically actuated automatic means to advance said wheel to a predetermined position and to thereafter withdraw said wheel and hold said wheel in withdrawn position, said automatic means including a rotating cam, connections through which said cam is effective to move said wheel head, connections through which said 20 automatic means gives said cam successive angular movements in opposite directions and brings said cam to rest in initial position, and means to adjust said cam while the cam is in motion to vary its operative effect.
- 25 4. In a grinding machine, a grinding wheel, a wheel head, and feeding mechanism for said wheel head, said feeding mechanism including a hydraulic cylinder and piston, manual means to start said piston in one direction, automatic means to reverse the direction of movement of said piston at the end of its travel in said first direction, and automatic means to bring said piston to rest on its return to initial position, said hydraulic mechanism including a reversing valve, a manually operated trip valve therefor, an automatically operated reversing trip valve 30 therefor, and automatic means to restore both trip valves to positions in which they subject said reversing valve to equal and mutually neutralized pressures on both ends.
- 35 5. In a grinding machine, a grinding wheel, a wheel head, and feeding mechanism for said wheel head, said feeding mechanism including a hydraulic cylinder and piston, manual means to start said piston in one direction, automatic 40 means to reverse the direction of movement of said piston at the end of its travel in said first direction, and automatic means to bring said piston to rest on its return to initial position, said hydraulic mechanism including a reversing valve, a manually operated trip valve therefor, an automatically operated reversing trip valve 45 therefor, and automatic means to restore both trip valves to positions in which they subject said reversing valve to equal and mutually neutralized pressures on both ends.
- 50 6. In a grinding machine, a work table, and a pair of swivel tables mounted on said work table and separately adjustable thereon, adjacent ends of said swivel tables having tailstocks secured thereto and the adjacent end portions of said tailstocks being substantially segmental about the swivel axis of each table when said tailstocks are secured in extreme outer position 55 on said tables, whereby clearance on close adjustment is secured.
7. In a grinding machine, a work table, a pair of swivel tables mounted on said work table and separately adjustable thereon, and a single 60 clamping device for said two swivel tables.
8. In a grinding machine, a work table, and a pair of swivel tables mounted on said work table and separately adjustable thereon, said swivel tables being pivoted to said work table near their 65 centers and being clamped to said work table at their inner and adjacent ends.
9. In a grinding machine, a work table, a pair of swivel tables mounted on said work table and separately adjustable angularly thereon, means 70 to secure each swivel table in separate angularly adjusted positions on said work table, and a separate head and tail stock for each swivel table mounted on and movable therewith, whereby each table rotatably supports a separate work- 75 piece.
10. In a grinding machine, a grinding wheel, a frame, a support slidable on said frame toward and from said grinding wheel, a work table slideable on said support parallel to said wheel axis, 80 and separate automatic feeding devices effective to feed said support toward and away from the grinding wheel, to feed said work table longitudinally, and to feed said grinding wheel toward and away from the work. 85
